UNITED STATES PATENT OFFICE.

ARTHUR M. FIELD, OF ASHEVILLE, NORTH CAROLINA.

DESIGN FOR A CHARM OR SIMILAR ARTICLE.

SPECIFICATION forming part of Design No. 30,004, dated January 17, 1899.

Application filed December 22, 1898. Serial No. 700,062. Term of patent 7 years.

To all whom it may concern:

Be it known that I, ARTHUR M. FIELD, of Asheville, in the county of Buncombe and State of North Carolina, have invented and 5 produced a new and original Design for a Charm or Similar Article, of which the following is a specification, reference being had to the accompanying drawings, forming part thereof.

10 Figure 1 is a front view of a charm, showing my design. Fig. 2 is a sectional view of the same.

15 The leading feature of my design consists in the circular rim surrounding the centrally-disposed ornament, presenting to the eye the appearance of a fly fish-hook.

20 In the drawings, *a* indicates the circular rim, and *bb* two circular disks of glass or other transparent material.

25 The ornament consists of the curved portion *c*, extending from the slightly-oblique central stem *c'*. From the upper end of the

central stem *c'* extend the raised threads *d*, radially disposed to form a fan-shaped ornamentation partly extending over the raised 25 feather ornament *e*. The irregularly-curved corded bead *f* extends from the upper end of the central stem *c'*, and from the lower end, at the junction of the curved hook-like portion *c* with the stem *c'*, the raised and curved 30 tail-shaped surface *g* extends. The transparent disks on each side of the central ornament enhance the effect of the ornamentation.

Having thus described my invention, what I claim as new, and desire to secure by Letters 35 Patent, is—

The design for a charm or similar article herein shown and described.

In witness whereof I have hereunto set my hand.

ARTHUR M. FIELD.
